UNITED STATES PATENT OFFICE.

LUCIAN W. BUGBEE, OF INDIANAPOLIS, INDIANA, ASSIGNOR TO ONEPIECE BIFOCAL LENS COMPANY, OF INDIANAPOLIS, INDIANA, A CORPORATION.

PROCESS OF GENERATING A DEPRESSED BIFOCAL LENS.

Application filed July 5, 1923. Serial No. 649,650.

To all whom it may concern:

Be it known that I, LUCIAN W. BUGBEE, a citizen of the United States, and a resident of Indianapolis, county of Marion, and 5 State of Indiana, have invented a certain new and useful Process of Generating a Depressed Bifocal Lens; and I do hereby declare that the following is a full, clear, and exact description thereof, reference being had to the accompanying drawings, in 10 which like numerals refer to like parts.

The object of this invention is to cheapen the manufacture of what are known as depressed onepiece bifocal lenses, that is, such 15 lenses with the reading field depressed relative to the distance field. This process shortens the time required to form and polish the reading field and form the shoulder between the two fields.

20 The chief feature of the invention consists in grinding the reading field smaller in diameter than desired, with a slightly raised surface at the middle of the reading field. Then the reading field is ground 25 and the shoulder formed by a grinding button of a diameter slightly greater than the radius of the reading field so that when 30 it is placed on the slightly raised surface on the center of the reading field, it will 35 reach beyond the margin of the reading field and overlap a portion of the surrounding or distance field and grind it away to form a shoulder.

In the process heretofore employed in 35 this art to make such lenses, the blank was ground so that the reading surface at the beginning would have its full required diameter, as shown by Letters Patent to me, No. 1,487,715, dated March 25, 1924, and 40 thereafter a grinding button substantially one-half the diameter of the reading field was required to be employed to grind the whole reading surface away until the required depression of the reading field and 45 size of the shoulder were produced. The object of the present invention is to quicken and cheapen the manufacture of such lenses by shortening the last operation referred to, namely, that of generating the 50 reading segment so as to depress it and provide the desired shoulder.

The full nature of the invention will be understood from the accompanying drawings and the following description and 55 claims:

In the drawings, Figure 1 is a central section of a target blank for making depressed bifocal lenses, showing the same in the finished form of a blank. Fig. 2 is the blank at the end of the first grinding 60 operation. Fig. 3 is a side view of the grinder for primarily generating the two bifocal surfaces. Fig. 4 is a section of a central portion of Fig. 2 on an enlarged scale with the button grinder in place 65 thereon. Fig. 5 is similar to Fig. 4 after the button grinder has operated.

The blank sought to be formed is shown in Fig. 1 and consists of a single piece of glass of target form which has been finished 70 on the bifocal side thereof so as to have a central depressed reading field 10 and a surrounding distance field 11. The target blank shown in Fig. 1 is not finished on the opposite side, but said target blank is centrally split and the two halves thereof sold and shipped from the manufacturer to the optician who finishes the back or prescription side according to the desired prescription and then edges the two half blanks 75 to form a pair of finished lenses, as has been customary in this art for several years. It is observed that in this type of onepiece bifocal lens blank, see Fig. 5, the reading field is depressed with reference to the distance field so that there is a distinct shoulder 12 at the division between the two fields.

Heretofore in making these lenses one method which has been employed has been to simultaneously grind and generate 90 roughly the two bifocal surfaces so that they practically merge into each other. In that form, the center of the reading field is lower than any other part of the reading field or of the lens blank. Then in the second step of the operation the reading field was further ground so as to depress the reading field and make the shoulder 12, as shown in Fig. 5. The reading field in this form as originally ground was of the full 95 required diameter of the reading field in the finished blank and the grinding button was required to grind the whole reading surface away until the required depth of the reading field and elevation of the shoulder 100 was attained. One drawback in this old operation was that the grinding button ground faster at the center of the reading field than it did at the margin thereof and that trouble, in addition to the long grind- 105 110

ing operation necessary to grind the reading surface entirely away, increased the expensiveness of said lenses.

In the present invention I make the 5 grinder 15 with a shallow recess 16 concentric of the zone 17 which generates the central part of the target blank. This leaves a slightly raised surface 18 at the middle of the reading field shown in Figs. 2 and 10 4. Also the zone 17 of the grinder is made relatively narrower than the diameter of the desired reading segment so that it produces a relatively narrow reading segment or portion. A grinding button 14 of the 15 usual size for said reading segment is next employed for further grinding and generating the reading segment. This button is one-half the diameter of the ultimate and desired reading field, but is of greater diameter than one-half of the diameter of the 20 reading field shown in Figs. 2 and 4, as generated in the first operation in this process.

Hence the button 14 in this process over- 25 laps the edge of the distance field somewhat, as shown in Fig. 4. It extends from the raised surface 18 at the center of the reading field to a point two or three m. m. beyond the margin of the reading field which 30 results from the first grinding operation. The intermediate portion of the button 14 does not touch the reading field for in generating the reading field in the first operation, as seen in Fig. 2, it has been ground down 35 or depressed to some extent. The chief function of the second operation, employing the grinding button 14, is to grind the shoulder so as to make the reading field of the desired diameter and make the shoulder 40 sharp and accurate. Therefore, all the grinding that is necessary in this second operation, according to the present invention, is the grinding down of the distance field at the shoulder and of the slightly raised 45 surface 18 at the center of the reading field. This grinding is a very short operation because the body of the grinding button does not have to grind away any of the glass. The central raised surface 18 also serves 50 to prevent the grinding button from digging into the center of the reading field and thus

changing the curvature thereof. Preferably the size of this raised surface 18 should be such that it would take the grinding button to remove it and form the shoulder 55 12. By this process the required shoulder is obtained in about one-tenth of the time required by the old process, and there is also less danger of changing the curvature of the reading field. 60

The invention claimed is:

1. In the process of making bifocal lenses, generating the distance field and reading field with the diameter of the reading field less than the desired ultimate diameter 65 thereof and with a raised surface at the center of the reading field, and simultaneously grinding away said raised surface and a concentric portion of the distance field to form the shoulder. 70

2. In the process of making bifocal lenses, generating the distance field and reading field with the diameter of the reading field less than the desired ultimate diameter thereof and with a raised surface at the 75 center of the reading field, and further grinding the reading field by a grinding tool having half the ultimate diameter of the reading field and placing one edge of said grinding tool on said raised surface 80 at the center of the reading field and the opposite edge of said button overlapping the adjacent edge of the distance field.

3. In the process of making bifocal lenses, generating the distance field and reading 85 field with the diameter of the reading field less than the desired ultimate diameter thereof and with a raised surface at the center of the reading field, and further grinding the reading field by a grinding 90 tool having half the ultimate diameter of the reading field and placing one edge of said grinding tool on said raised surface at the center of the reading field and the opposite edge of said button overlapping 95 the adjacent edge of the distance field and not touching the reading field between said opposite edges of the button until the grinding operation is substantially completed.

In witness whereof, I have hereunto affixed my signature.

LUCIAN W. BUGBEE.
